UNITED STATES PATENT OFFICE.

CHARLES D. FISCHER AND WALTER RUTKOWSKI, OF ENCAMPMENT, WYOMING.

TATTING-SHUTTLE WINDING DEVICE.

Application filed May 22, 1924. Serial No. 715,189.

To all whom it may concern:

Be it known that we, CHARLES D. FISCHER and WALTER RUTKOWSKI, citizens of the United States, residing at Encampment, in the county of Carbon and State of Wyoming, have invented certain new and useful Improvements in a Tatting-Shuttle Winding Device, of which the following is a specification.

10. This invention relates to new and useful improvements in winding devices for tatting shuttles and has for its principal object to provide a simple and efficient device which may be easily operated, means being provided for guiding the thread to the shuttle.

15. A further object of the invention is to provide a tatting shuttle winding device of the above mentioned character, wherein means is associated with the supporting frame for the shuttle for preventing the pinching and breaking of the thread by the points of the shuttle as the same rotates in the frame.

20. A still further object of the invention is to provide a tatting shuttle winding device of the above mentioned character, which is simple in construction, inexpensive, strong and durable and furthermore adapted for the purposes for which it is designated.

25. Other objects and advantages of this invention will become apparent during the course of the following description.

30. In the accompanying drawing forming part of this specification and in which like numerals designate like parts throughout the same:

Figure 1 is a plan elevation of our improved device.

Figure 2 is a side elevation thereof.

35. Figure 3 is a detail perspective view of the guide plate.

Figure 4 is a detail perspective view of the tatting shuttle, and

40. Figure 5 is a fragmentary detail view of the clutch provided on the crank handle.

45. In the drawing wherein for the purpose of illustration is shown the preferred embodiment of my invention, the numeral 1 designates generally a substantially U-shaped frame which is formed of sheet metal and the arms thereof have their intermediate portions bent inwardly and fastened together as illustrated at 4 whereby a handle portion 5 is provided and the free

55. ends of the arms 2 and 3 provide a means for receiving therebetween the tatting shuttle 6, the construction of which is well known in the art.

60. The tatting shuttle 6 is provided in the central portion of the plates comprising the same with the key hole shaped slots 7 and 8 respectively, the purpose of which is to provide a means for cooperation with the trunning 9 which is supported on the outer free end of the arm 2 and extends inwardly 65 therefrom while the slot 8 is adapted to receive the clutch 10 provided on the inner end of the crank shaft 11 which extends through a suitable bearing 12 provided in the outer end of the opposite arm 3 in the 70 manner clearly illustrated in Figure 1 of the drawing. A handle such as is illustrated at 13 is associated with the crank shaft to provide a means for actuating the same whereby the tatting shuttle may be rotated 75 between the outer ends of the arms 2 and 3 of the substantially U-shaped frame 1.

80. Disposed between the inwardly bent portions of the arms of the U-shaped frame 1 and secured therein by means of the fastening member 4 is the guide plate 14, the construction of which is more clearly illustrated in Figure 3. The plate is of substantially the same width as the width of the band comprising the frame and the 85 same has its forward end beveled as illustrated at 15 and the same is disposed between the outer ends of the arms 2 and 3 within the path of rotation of the tatting shuttle in the manner as illustrated more clearly 90 in Figure 1. The plate is provided with the openings 16 whereby the fastening means 4 may extend therethrough to support the same in position in the frame.

95. Formed on the forward end of the plate 95 and cooperating with the beveled edge thereof are the hooks 17 and through which is adapted to extend the thread A which is to be wound on the tatting shuttle in the manner well known in the art.

100. The provision of the hooks on the forward beveled end of the plate provides a means for guiding the thread to the tatting shuttle and furthermore will prevent the pointed end of the tatting shuttle from pinching or 105 otherwise breaking the thread as the shuttle rotates between the free ends of the arms. It will of course be understood that when

the handle 13 of the crank shaft 11 is turned, the tatting shuttle will rotate in such a manner as to cause the forward beveled end of the plate to be wedged between the sides of the tatting shuttle so that the same will extend into the shuttle without causing any interference with the rotation of the shuttle.

In winding the thread on the tatting shuttle, the shuttle is placed in position within the frame and the operator holds the frame by the handle 5 in one hand and turns the crank shaft 11 through the medium of the handle 13 in the other hand thereby winding the thread on the shuttle in a comparatively simple and efficient manner.

The simplicity of our device enables the same to be manufactured at a very low cost and will further be strong and durable. The provision of the thread guide plate will prevent the thread from being broken by the pointed ends of the shuttle and will furthermore hold the thread in such a position as to enable the same to be wound on the shuttle in a comparatively short time without any danger of the thread becoming entangled.

While we have shown the preferred embodiment of our invention, it is to be understood that various changes in the size, shape and arrangement of parts may be resorted to without departing from the spirit of the invention and the scope of the appended claims.

Having thus described our invention, what we claim is:—

1. A tatting shuttle winding device comprising a substantially U-shaped frame, a shuttle rotatably supported therein, means for actuating the same, a thread guide on the frame and disposed in the path of the rotation of the shuttle, said guide comprising a plate disposed between the arms of the U-shaped frame and secured thereto, and hooks provided on the forward end thereof to receive the thread.

2. A tatting shuttle winding device comprising a substantially U-shaped frame, the intermediate portions of the arms thereof being bent inwardly and fastened together to provide a handle at the closed end of the frame, a shuttle rotatably supported between the outer free ends of the arms of the frame, means for rotating said shuttle, a plate secured between the inwardly bent portions of the arms of the frame, the forward end of the plate being beveled, hooks formed on the forward beveled end of the plate and providing a guide means for the thread to be wound on the shuttle, a portion of the forward beveled end of the plate being disposed within the path of rotation of the shuttle.

In testimony whereof we affix our signatures.

CHARLES D. FISCHER.
WALTER RUTKOWSKI.
